Application January 10, 1931, Serial No. 507,872

22 Claims. (Cl. 77—3)

This invention relates to material working apparatus and more particularly to hydraulically operated automatic boring machines.

Material working apparatus, such as boring machines, are frequently employed for heavy duty work, as, for example, for boring heavy castings and the like. Due to the weight of these castings, it is not possible to manually lift and shift them, and therefore means must be provided for mechanically controlling the shifting of the work piece or casting to be acted upon by the boring machine.

It is one of the important objects of the present invention to provide a machine, whereby the necessity for manual control or manipulation is reduced to a minimum, and to this end we propose to provide an automatically operable machine, in which cutting operations may be automatically performed with a minimum amount of skill and effort on the part of an operator.

Another object of the present invention is to provide a machine, as above set forth, in which practically no time is lost in changing the work pieces or castings upon the completion of one cycle of operation, and in this connection we propose to provide a shiftable table or support, which will enable a work piece or casting previously acted upon by the boring tools, to be removed and another substituted in its place while a boring operation is being automatically performed upon another work piece carried by the table. In this manner the operator may employ the time required for the machine to complete a cycle of operation, for removing a finished work piece and mounting another in its place. This time element, coupled with the fact that one operator may control the mounting of the work piece, as well as the operation of the machine, makes for a decided increase in operating efficiency and economic production.

More specifically, it may be stated that our invention contemplates the provision of a material working apparatus, such as a boring machine, which may be controlled by the mere shifting of a control handle in a given direction, the shifting of this handle by an operator serving to initiate a cycle of operation, which consists in the rapid advancement of a spindle head toward the work piece, the automatic coupling of the spindles with the boring tools, the automatic changing from rapid to feeding movement for cutting purposes, the automatic rapid reversal upon the completion of the cutting operation, and the automatic disengagement of the spindles from the boring tools.

A still further and more specific object is to provide, in combination with machines as above set forth, an improved automatically operable chuck mechanism which serves as an effective coupling means between the driving spindles and the boring tools. 5

Another object of the present invention is to provide, in combination with a machine of the general nature set forth above, a hydraulic control which serves to effect the automatic reciprocation of the spindle head. 10

A further object of the present invention is to eliminate the performance of manual operations which have been necessary heretofore in connection with the manipulation of conventional types of boring machines and the like, and to this end we propose to render the operation of the machine, during each complete cycle, fully automatic. 15

A still further and more specific object of the present invention is to provide, in combination with a self-contained spindle or boring head, means for automatically controlling a cycle of reciprocation of said head and an automatically operable chuck mechanism, which is adapted to 25 couple and uncouple boring bars with respect to the spindles of said head during a proper predetermined interval of the cycle of operation.

The foregoing and numerous other objects and advantages will be more apparent from the following detailed description when considered in connection with the accompanying drawings, wherein— 30

Figure 1 is a front elevational view of a boring machine, which is illustrative of one embodiment 35 of my invention, the boring head thereof being shown in an advance position in readiness to begin its feeding approach movement;

Figure 2 is a central vertical sectional view of the rotary work supporting table and associated mechanism for lifting same, said view being taken substantially along the line 2—2 of Figure 1; 40

Figure 3 is a plan view of the device shown in Figure 1, with the spindle head shown in its starting position as distinguished from Figure 1, 45 wherein the spindle head is shown in operative engagement with the boring tools;

Figure 4 is an enlarged fragmentary sectional view of one of the chuck mechanisms, said view disclosing the chuck in operative driving relation with the boring tool; 50

Figure 5 is an elevational view, shown partly in section, of the chuck mechanisms, boring tools, and retainer bars;

Figure 6 discloses the relative positions of the 55

parts comprising the chuck mechanism prior to the operative association thereof with a boring tool or bar;

5 Figure 7 is a view similar to Figure 6, disclosing the boring tool entering the chuck mechanism;

Figure 8 is a transverse sectional view of the chuck mechanism taken substantially along the line 8—8 of Figure 6;

10 Figure 9 is a vertical transverse sectional view taken substantially along the line 9—9 of Figure 5;

Figure 10 is an enlarged elevational view of the mechanism for controlling the hydraulic actuator;

15 Figure 11 discloses said control mechanism as viewed from the right of Figure 10;

Figure 12 is a plan sectional view taken substantially along the line 12—12 of Figure 10;

20 Figure 13 is a fragmentary elevational view to more clearly illustrate the structural and functional characteristics of the notched lever arm;

Figure 14 is an enlarged vertical sectional view of the spindle or boring head taken substantially along the line 14—14 of Figures 3 and 15;

25 Figure 15 is a vertical sectional view of the spindle head taken substantially along the line 15—15 of Figures 3 and 14; and

30 Figure 16 is a semi-diagrammatic view disclosing the hydraulic system of control for reciprocating the spindle or boring head.

Referring now to the drawings more in detail wherein like numerals have been employed to designate similar parts throughout the various figures, it will be observed that for the purpose of illustrating one practical embodiment of the invention, we have shown the same in association with a material or metal working apparatus of the type which is commonly referred to as a boring machine. This boring machine as shown in the drawings includes a frame or bed 20, which serves as a support for a reciprocable spindle or boring head, which is designated generally by the numeral 22, Figures 1 and 3, later to be described. Positioned adjacent the right end of the bed 20, 40 Figure 1, is a second frame or bed 24, which serves as a support for a rotary work supporting table 26.

Work supporting table

50 This table 26 is of circular construction and is centrally supported by means of an upright hollow support member 28, Figure 2. The lower extremity of this support member 28 is mounted upon an anti-friction or friction-reducing bearing 30. A sleeve 32 mounted upon a cylindrical central portion of the bed 24 serves as a bearing for the rotary upright support 28 and permits said support to not only rotate therein, but also to be vertically shifted with respect thereto. The vertical shifting of the support 28 is accomplished through the agency of a foot pedal 34, which is pivoted at its inner extremity upon a member 36. The pedal 34 is connected by means of a link 38 with an arm 40, which is in turn mounted upon a shaft 42. This shaft 42 carries a cam 44 and when the pedal 34 is urged downwardly, the cam is rotated so as to effect the upward movement of the support 28 and consequently the raising of the table 26.

Upon lowering the foot pedal 34, a latch pin 70 46 is urged downwardly against a spring 48, said pin being connected with the pedal 34 by means of a link 50. Thus, when the table 26 is raised, it automatically becomes disengaged from the latch pin 46 so as to permit the free rotation thereof. The table 26 serves as a support for a

pair of fixtures 52. These fixtures are identical in construction, and are designed to support a work piece, such as a work piece or casting 54 shown in Figures 1 and 3. The fixtures 52 are each provided with upright sections 56, 58, 60, and 62, Figure 1, which serve as supports for boring tools or bars 64 and 64a. The work piece or casting as shown in the drawings, namely, the work piece 54 comprises three spaced walls or sections 66, 68, and 70, Figure 1, which are provided with apertures to be bored. Tool bits 72 mounted within the bars 64 and 64a are adapted, when rotation is imparted to the bars and said bars are urged longitudinally to the right, Figure 1, to bore into the bearing surfaces of the work piece. The operation of the boring bars will be more apparent as the description progresses. It will be noted that the fixtures 52 are so disposed upon the rotary table 26, that, when the table occupies the position shown in Figure 20 3, the boring bars 64 and 64a associated with one of the work pieces will be positioned in alignment with companion spindles 74 and 74a respectively of the boring head 22. The latch pin 46 serves to secure the table 26 against rotation, and as soon as an operation upon the work piece has been completed, the operator depresses the pin 46 by stepping upon the pedal 34, thereby enabling the boring bars of the other work piece to be shifted into alignment with the above mentioned spindles. 30 Clamping members 75 pivotally supported upon suitable brackets 77, Figure 1, may be employed to further secure the table 26 against rotation. These clamping members may be swung out of engagement with the table when not in use. Obviously, in order to rotate the table when these clamping members occupy the position shown in Figure 1, it is necessary to disengage said members from the table.

Spindle or boring head

40 The spindle or boring head 22 includes a main housing or casting 76 which is mounted upon suitable guide ways 78, Figure 3, provided along the upper surface of the bed 20. The housing 45 76 encloses and supports the spindles 74 and 74a, as clearly shown in Figures 14 and 15. Rotation is imparted to these spindles in any suitable manner, as, for example, through the agency of gears 80 and 80a which are driven from a common gear 82. This gear 82 is mounted upon a shaft 84 which is driven from a drive shaft 86 through a pair of bevel gears 88 and 90, Figures 14 and 15. The bevel gear 90 is mounted upon a drive shaft 92, and suitable pick-off gears 94 and 96 provide the driving connections between the shaft 92 and a second drive shaft 98. These pick-off or change gears 94 and 96 may be changed in accordance with required spindle speeds. Power is supplied to the shaft 98 from an electric motor 100 which is connected with the shaft by means of a suitable chain 102 meshing with a large drive gear 104. Thus it will be apparent that power for rotating the spindles 74 and 74a is supplied from the electric motor 100 and the entire mechanism presents a self-contained or unitary structure which is adapted to be reciprocated along the guide ways 78. A cover plate 106 may be removed to facilitate the changing of the gears 94 and 96. A bracket 108, Figure 14, depending from the boring head is coupled with one end of a piston rod 110, and this piston rod 110 forms a part of a hydraulic actuator designated generally by the numeral 112, Figure 16. 75

Hydraulic actuator system

The actuator 112 includes a suitable cylinder 114 and a piston 116 which is provided at the inner end of the piston rod 110, Figure 16. The cylinder 114 is mounted in any suitable manner within the bed 20 beneath the ways 78, as indicated in Figure 15. It will be apparent that fluid under pressure introduced within the right end of the actuator cylinder 114, Figure 16, will cause the boring head to be shifted to the left, while fluid introduced within the left end of said cylinder will cause the head to be shifted to the right. The present invention is not concerned with the particular type of means for delivering fluid, such as oil under pressure, to the actuator 112, except in so far as such means or mechanism enters into the general combination of the remaining machine elements. Therefore, it is not essential for a clear understanding of the present invention that hydraulic mechanisms, such as fluid pumps and the like or valves for controlling fluid from said pumps, be specifically described in this application. In order to explain the functioning of the hydraulic actuator 112, we have shown a pumping and valve unit designated generally by the numeral 118, Figure 16, which is of conventional design. This equipment is commonly referred to by the trade as "oilgear" equipment and is illustrated in the patent to J. P. Ferris, No. 1,753,562, dated April 8, 1930. Said equipment includes a main control valve 120, which is adapted to be shifted to five different positions for controlling the flow of fluid from pumping mechanism housed within a casing 122. A handle 124 is shifted for the purpose of varying the displacement of the pumping mechanism housed within the casing 122, and when a shiftable member or rod 126 of the valve 120 occupies the position shown in Figure 16, no fluid is delivered to the actuator 112. This position is commonly referred to as the neutral position of the valve. The various shifted positions of the valve member 126, which are employed in connection with the present invention, are designated in Figure 16. It will suffice to say that when the valve member 126 is shifted to its extreme left position, Figure 16, fluid will be delivered to the actuator 112 for the purpose of imparting rapid traverse or rapid approach movement to the boring head 22, that is, rapid movement to the right, Figures 1, 3, and 16. When the valve member 126 is shifted to the position designated as "feed approach" position, fluid is delivered to the actuator so as to impart a slower or feeding approach movement to the boring head. When the valve member is shifted to its extreme right position designated as "rapid reverse" position, Figure 16, fluid will be delivered at a rapid rate in a reverse direction to the actuator so as to effect the rapid reverse movement of the boring or spindle head to the left. Suitable pipe lines 128 and 130, Figure 16, serve to conduct the fluid toward and away from the actuator cylinder 114, while a pressure gauge 132 serves to indicate the pressure of the fluid within the hydraulic actuator system. Power is supplied to the pumping unit 118 from a suitable electric motor 134, Figure 3, which is connected by means of a chain 136 with the mechanism housed within the casing 122.

Control mechanism

The hydraulic actuator system described above is controlled by means of a mechanism designated generally by the numeral 138, Figures 1,

16, and 10 to 13 inclusive. This mechanism includes a main control handle 140, which is pivotally carried by a shaft 142 on the front side of the bed 20. A short arm 144 formed integral with and extending at substantially right angles to the handle 140 is pivotally connected at its outer extremity with the upper end of an extensible shifter rod 146. The lower end of this extensible rod 146 is pivotally connected with the free end of a lever arm 148 which is mounted upon a shaft 150. This shaft 150 extends transversely of the bed 20 and is connected at its rearward extremity with a second arm 152. The outer end of this arm 152 makes a slotted connection with one extremity of a connecting rod 154 which is pivotally connected with the valve member 126, as clearly shown in Figure 16. A coiled spring 156 is interposed between the free end of the arm 144 and an anchor member 158 which is secured to the bed 20. This spring 156 constantly urges the arm 144 downwardly, thereby serving to continuously urge the control handle 140 to the right, Figures 1, 10, and 16.

Carried on the inner side of the handle 140 is a lug or finger 160, which cooperates with a horizontally disposed pivoted arm or lever 162 to secure the control handle in various positions of adjustment. Referring to Figures 10 and 13, it will be seen that the lever arm 162 is provided with a plurality of stops 164, 166, 168, and 170. When the handle 140 occupies the substantially vertical position shown in Figure 10, the finger or lug 160 will be positioned against the stop 164, the spring 156 serving in this instance to urge the finger against the stop, and a second coiled spring 172 serving to urge the lever arm 162 upwardly against the finger 160. This spring 172 is interposed between the lower side of the arm 162 and a suitable bracket or socket 174, Figure 10. If the handle 140 is swung to its extreme left position, which position is indicated by the line in Figures 10 and 13, designated by the term "Rapid approach", the finger 160 will be lodged against the stop 168. The shifting of the handle 140 to this position causes the valve 120 to be conditioned so as to effect the rapid traverse or approach movement of the actuator and consequently the rapid approach of the boring head 22. As the boring head reaches the limit of its rapid approach movement, which is determined by the position of the boring bars 64 and 64a, a dog 176, adjustably supported along the front side of the head 22, is moved into engagement with a companion abutment 178 carried by the arm 162 Figure 10. This causes said arm to be depressed sufficiently to effect the clearance of the finger 160 past the stop 168, thereby causing said finger to be shifted into engagement with the stop 166. This position of the handle 140 is designated as the feed approach position, Figures 10 and 13. In this position the valve 120 is conditioned to impart a feeding, forward or approach movement to the boring head 22, which movement is employed during the cutting operation of the boring bars. When the boring bars reach the limit of their cutting stroke, a second dog 180 engages the abutment 178, thereby further depressing the lever 162. This shifting of the arm 162 is sufficient to cause the finger 160 to clear the neutral stop 164 and to be carried into engagement with the rapid reverse stop 170. With the control handle 140 in this position, the valve 120 is conditioned to effect rapid reverse movement to the boring head. As the head approaches its starting position, a dog 182 shifts the handle 140 to

the left. As soon as the handle reaches the neutral position designated in Figure 10, the valve 120 is thrown into neutral, thereby arresting the movement of the hydraulic actuator 112.

- 5 In the manner described above, a complete cycle of operation or reciprocation of the head 22 is automatically effected by merely shifting the control handle to its extreme left or rapid approach position. Upon the completion of this cycle of 10 operation, the operator elevates the table 26 by stepping upon the pedal 34, rotates said table so as to carry the other work into alignment with the spindles, lowers the table, and again initiates the cycle of operation by a single manipulation 15 of the control handle 140. During this cycle of operation the operator removes the work piece previously acted upon and replaces it with another.

Automatic chuck mechanisms

- 20 Thus far the cycle of operation of the boring head has been described, but no description has been given of our improved automatically operable chuck mechanisms designated generally by 25 the numerals 184 and 184a, Figures 1, and 3 to 9 inclusive. These mechanisms are sometimes referred to as automatic pick-up chucks because it is their function to automatically pick up or grip their respective boring bar as the head 22 reaches the limit of its rapid approach position. It will be seen that these pick-up chucks or chuck mechanisms 184 and 184a are identical in construction, and therefore a description of one will suffice for both. Each of said chuck mechanisms includes a sleeve 186, which is mounted upon and keyed to the outer extremity of its companion spindle. Each of the spindles 74 and 74a is reduced to receive one of said sleeves, as clearly shown in Figures 5 to 7 inclusive, and a set screw 40 188 serves as an additional means for securing said sleeves upon the spindle. A collar 190 encircles the sleeve 186, and a coiled spring 192 is interposed between an annular shoulder 194 and said collar. An annular member 196 which is depressed within the sleeve 186, serves as an abutment to prevent the collar 190 from moving beyond the position shown in Figures 4 and 5. The collar 190 carries a plurality of equally spaced radially disposed pins 198, and these pins 50 are urged inwardly by means of suitable coiled springs 200. An annular member or ring 202 serves to prevent the outward displacement of the pins. These pins 198 are companion to pins 198a mounted within the sleeve 186.
- 55 Before the clutch mechanisms 184 and 184a are moved into operative association with their companion boring bars 64 and 64a, the collar 190 occupies the position shown in Figure 6. In this position the pins 198 are urged within companion 60 recesses 204 of the sleeve 186, and thus secure the collar against movement to the right in response to the action of the coiled spring 192. As the sleeve 186 is moved toward the adjacent end of its companion boring bar, a cap 206 secured 65 to the bar is sheathed by the sleeve 186, as clearly shown in Figure 7. The outer end of the cap 206 is provided with a conical surface 208, and it will be seen that as the sleeve passes over the cap, locking balls 210 housed within the sleeve 186 70 are urged outwardly to the position shown in Figure 7, and the conical surface 208 engages the inner ends of the pins 198a. Continued movement to the right of the sleeve 186 causes the pins 198a to be urged outwardly, thereby 75 causing the pins 198 to clear the outer ends of

the recesses 204. The spring 192 urges the collar 190 to the right, and when the semi-spherical cavities 210a provided within the cap 206 register with the balls 210, the collar 190 is automatically shifted to the position shown in Figures 4 and 5, thereby causing the balls to be urged into the cavities 210a. This establishes a driving connection between the sleeve 186 and the cap 206. The cap 206 is coupled with the boring bar by means of suitable keys 212 and also by means of screws 10 214. The setting of the dog 176, Figure 10, is such as to effect the shifting of the control handle 140 to the feed approach position contemporaneously with the coupling of the sleeve 186 with the cap 206, so that as the boring head is advanced 15 at a feeding rate, the boring bars 64 and 64a are rotated.

20 The extremities of the boring bars 64 and 64a oppositely disposed from the clutch mechanisms 184 and 184a bear against companion retainer 20 bars 216 and 216a respectively. These retainer bars are housed within suitable supports 218 mounted upon the upright section 62 of the fixture 52, and are provided with annular recesses or grooves 220 and 222. A pin 224 is continuously urged toward the retainer bars through the action of a spring 226, Figure 5. As the clutch mechanisms are initially carried into operative association with the boring bars, the retainer bars are positioned as shown in Figure 5 30 with the pins 224 lodged within the annular recesses 220. The resistance against longitudinal displacement of the retainer bars 216 to the right, Figure 5, which is set up by the pins 224, is greater than the resistance experienced by the 35 entrance of the boring bars within the sleeve 186, and thus serves as a temporary abutment to insure the coupling of the sleeve with the boring bar. In other words, if some means were not provided to prevent longitudinal displacement 40 of the bars to the right as said bars are initially engaged by the clutch mechanisms, the resistance set up by the pins 198a and the balls 210 acting against the cap 186 might be sufficient to urge the bars to the right and thereby prevent 45 the completion of the coupling action of said clutch mechanisms. When the clutching operation has been completed and the bars are positively urged at a feeding rate to the right, Figure 5, the force of the pins 224 is overcome and the 50 retainer bars are shifted to the right. The annular grooves 222 receive the pins 224 when the boring operation has been completed.

55 As the boring bars approach the completion of their cutting stroke to the right, Figures 1 and 5, 55 a lever 228 pivotally supported by a bracket 230 on the boring head is moved into engagement with an abutment 232. This abutment 232 is continuously urged to the left through the action of a coiled spring 234 housed within the upper 60 end of a suitable bracket 236. The free upper end of the lever arm 228 provides a yoke 238, Figure 9, and this yoke is coupled with a secondary yoke 240. This secondary yoke 240 is adapted to engage the collar 190 associated with the 65 clutch mechanism 184a and when the spring 234 has been compressed sufficiently to overcome the action of the spring 192, continued advancement of the collar 190 will be arrested and said collar will eventually occupy the position shown in Figure 7. With the collar in this position, the balls 210 are free to be moved outwardly as a reverse movement is imparted to the sleeves 186. By employing the spring 234, the abutment 232 is held against the lever 228 for a sufficient interval dur- 70 75

ing the reverse movement of the head so as to insure the uncoupling of the clutch mechanisms from the boring bars. It will also be noted that we employ a plunger 242 on the left side of the lever 228, Figure 5, which, through the action of a suitable spring 244, continuously urges the lever to the right. By this mechanism the lever is immediately swung to the right as it leaves the abutment 232. It will also be seen that in the 10 particular disclosed embodiment of the invention we have shown the collars 190 of the clutch mechanism coupled together, so that the operation of the lever 228 will effect the simultaneous actuation of both clutch mechanisms. Obviously 15 these clutch mechanisms may be constructed so as to operate independently of each other by simply employing an independently operable lever for each mechanism. For the purpose of simplifying the description and the disclosure, we have 20 shown a single lever for simultaneously operating both clutch mechanisms.

From the foregoing it will be apparent that upon the reversal of the boring head, the clutch mechanisms function to uncouple the boring bars 25 from the spindles, and as the head is being automatically returned to its starting position, the operator may rotate the table 26 so as to locate a second work piece in position to be subsequently acted upon. Before the boring head is again 30 moved forwardly the retainer bars 210 are manually urged to the left by simply gripping the outer ends thereof and shifting the same until the pins 224 are received by the recesses 220.

Statement of operation

35 In operating the above described apparatus, the work piece 54 is first mounted within its companion fixture 52, and the boring bars 64 and 64a are properly inserted within the work piece. The 40 table 26 is positioned so as to locate the boring bars in alinement with the spindles and chuck mechanisms associated therewith, and the motors 100 and 134 are energized. The motor 100 causes rotation of the spindles 74 and 74a, while 45 the motor 134 drives the pumping mechanism housed within the casing 122. The operating handle 140 is then shifted to the left from the neutral position shown in Figure 10 to the rapid approach position. In this position the finger 160 engages a stop 168 of the lever arm 162, and the main control valve 120 is conditioned to deliver fluid at a high rate of displacement to the left end of the actuator cylinder 14, Figure 16. This causes a rapid approach or forward movement 50 of the boring head 22 until the clutch mechanisms 184 and 184a are moved into operative association with the caps 206 of the boring bars 64 and 64a respectively. At this time the dog 176, Figure 10, carried by the head 22 engages 55 the abutment 178, and thereby depresses the lever 162 sufficiently so as to effect the automatic shifting of the control handle 140 to the feed approach position, at which time the finger 160 engages the stop 166. A feeding movement is 60 now imparted to the boring head. As the sleeves 186 of the clutch mechanisms reach the position shown in Figure 7, the locking balls 210 are urged outwardly and continued movement causes the pins 198 and 198a to be shifted outwardly against 65 the action of the springs 200. The coiled springs 192 serve to suddenly urge the collars 190 to the right, thereby causing the balls 210 to be moved into the peripheral recesses 210a. This action 70 serves to positively couple the sleeves 186 with 75 their respective boring bars, and thus rotation is

imparted to the boring bars during the feeding approach movement of the boring head. During this initial coupling operation the retainer bars 210 serve to prevent longitudinal movement of the boring bars until said coupling operation has been completed and the boring bars are positively urged at a feeding rate to the right, Figure 5. Upon completion of the cutting stroke of the boring bars, the abutment 232 is engaged by the lever 228, and the yoke 240 carried by said lever arrests the advancement of the collars 190, thereby releasing the locking balls and automatically uncoupling the clutch mechanisms from the boring bars. At the same instant the dog 180 engages the abutment 178, Figure 10, thereby releasing the finger 160, and the spring 156 causes the control handle 140 to be shifted to its rapid reverse position. The boring head is now reversed at a rapid rate to its starting position. As soon as the clutch mechanisms have been disengaged and are separated from their respective boring bars, the operator steps upon the foot pedal 34, thereby releasing the table from the latch spring 46, Figure 2. The table 26 is then rotated so as to carry another work piece 25 equipped with boring bars into proper position for subsequent engagement with the clutch mechanisms. As the boring head reaches its starting position, the dog 182 moves the control handle 140 to the neutral position shown in Figure 10, 30 and the hydraulic actuator is rendered functionally inoperative. To initiate another cycle of operation, it is only necessary for the operator to again shift the handle to the left. While the machine is performing its cycle of operation, the 35 operator removes the work piece previously acted upon and replaces it with another work piece and a pair of boring bars.

Summary

40 From the foregoing it will be apparent that our invention reduces to a minimum the amount of effort and skill required by an operator in controlling a machine of the type set forth above. The above described cycle of operation is occasioned by merely shifting an operating handle to a given position, and the automatic picking up and releasing of the boring bars enable the machine to function uninterruptedly during this 45 cycle of operation. By employing a machine of 50 our improved design, the operator is relieved of the necessity of manually coupling and uncoupling the spindles with respect to the boring bars and is further relieved of the necessity of manually controlling the rate of travel of the boring 55 head. In view of the fact that the machine automatically performs a complete cycle of operation, the operator is afforded sufficient time to remove a completed work piece and mount another work 60 piece on the table, so that, when the operating 65 cycle has been completed, the new work piece may be immediately shifted into position. In this manner the functioning of the machine is practically continuous, and only a very brief interval is required to impart partial rotary movement to the table in order to position the new work piece in alinement with the spindles and to position the work piece acted upon in a convenient location for removal.

The "pick-up" clutch mechanisms 184 and 184a 70 are of very practical design and serve as very efficient means for automatically coupling and uncoupling the spindles and boring bars. These clutch mechanisms may be made by practicing conventional machine shop methods, and, in fact, 75

the entire machine structure is of a very practical design. Obviously the clutch mechanisms are not limited for use in connection with boring machines, but are capable of application in any 5 instance where it is desired to couple and uncouple a rotary driving member with respect to another member. Obviously the invention is not limited to the specific clutch mechanism design shown in the drawings, but is capable of numerous other modifications and variations without 10 departing from the spirit and scope thereof.

It will also be noted that the above described machine is not only automatically operable, but is capable of being manually controlled by merely shifting the levers 140 and 162. This manual control may be readily effected by merely gripping the lever 162 with one hand so as to disengage the stops thereon from the finger 160, and then manipulating the lever 140 with the 20 other hand in order to control the speeds and direction of movement of the boring head. While we have shown one specific hydraulic circuit arrangement of conventional design, it should be understood that we contemplate employing any 25 other type of hydraulic actuator system of control which readily lends itself for use in connection with the shifting of a machine element, such as the boring head 22. Various other types of index tables having a plurality of stations for 30 receiving and discharging work pieces may also be employed without departing from the spirit and scope of the appended claims.

Attention is also directed to the fact that while in the present application, we have shown the 35 chuck mechanism mounted upon one of the spindles of boring head, this mechanism may be mounted in association with the boring bar. This latter arrangement is shown in our co-pending application, Serial No. 515,779, filed February 14, 40 1931, relating to boring machines. In other words, the present invention is not limited to the specific manner in which the chuck mechanism is mounted upon the boring machine.

Having thus described our invention, what we 45 claim as new and desire to secure by Letters Patent is:

1. A boring machine of the class described including a support, a spindle head for simultaneously boring a plurality of spaced sections 50 in a work piece including a spindle for driving a boring tool, an index table having a plurality of stations, said table being manually shiftable independently of the spindle head, one of said stations being adapted to locate a work piece in position to be acted upon by a tool having axially 55 spaced cutting elements driven by said spindle and another of said stations being adapted for receiving and dispatching work pieces, spaced bearing members on said table for the rotary cutting tool, which bearing members are operable as supports independently of the work piece, certain of said bearing members being interposed between the spaced sections of said work piece, whereby to accurately maintain a preselected position of said tool, hydraulic mechanism for reciprocating said head, and means for automatically controlling the functioning of said hydraulic mechanism.

2. In material working apparatus for simultaneously 70 boring a plurality of spaced sections in a work piece, a support, a spindle head for driving rotary cutting tools, said head being reciprocable upon said support, a shiftable work supporting table having a plurality of stations, 75 said table being manually shiftable independent-

ly of the spindle head, a rotary cutting tool adapted to be mounted at said stations and being further adapted for operative engagement with a spindle of said head, said cutting tool including a plurality of spaced cutting elements, spaced bearing means on said table for the rotary cutting tool which are operable as supports independently of the work piece, certain of the bearing sections being interposed between the spaced sections of the work piece, whereby to accurately 10 maintain a preselected position of the tool with respect to said work piece and means for controlling the reciprocation of said spindle head.

3. In material working apparatus, a support, a spindle head for driving rotary cutting tools, said head being horizontally reciprocable upon said support, a rotary work supporting table having a plurality of stations, rotary cutting tool having axially spaced cutter elements adapted to be mounted at said stations and being further adapted for operative engagement with a spindle of said head, means operable independently of a supported work-piece and providing a mounting for said cutting tools, means for controlling the reciprocation of said spindle head, and mechanism associated with a spindle of said head to effect the automatic coupling between said spindle and a rotary cutting tool supported on the table, said mechanism also including means for temporarily preventing the advancement of a tool until the coupling operation has been completed and for automatically releasing said tool to permit the continued advancement thereof when said coupling has been completed, whereby to effect the simultaneous cutting action of said spaced cutter elements upon the work.

4. In material working apparatus, driving means including a rotary member, a rotary cutting tool having a plurality of axially spaced cutter elements for engaging spaced work sections and adapted to be positioned in substantial alignment with said rotary driving means, said tool and rotary driving member being relatively, axially movable, a work carrier, a tool guiding and supporting means mounted directly upon said carrier for accurately maintaining a preselected position of the rotary cutting tool with respect to a work-piece, said tool guiding means including a plurality of spaced bearings, certain of said bearings being interposed between said axially spaced cutter elements, coupling mechanism for automatically connecting and disconnecting said rotary driving means and cutting tool, and means for preventing operative engagement of the tool with the work-piece until the coupling of the rotary driving means with the tool has been completed and for automatically releasing the tool to permit the continued advancement thereof when said coupling has been completed.

5. In material working apparatus, driving 60 means including a rotary member, a rotary cutting tool including a plurality of axially spaced cutter elements and adapted to be positioned in substantial alignment with said rotary driving means, a work carrier, a tool guiding and supporting means mounted directly upon said carrier for accurately maintaining a preselected position between the tool and a work-piece, said tool guiding means including a plurality of axially spaced bearings, certain of said bearings being interposed between said spaced cutter elements, said tool and rotary driving member being relatively, axially movable, abutment means 70 for preventing operative engagement of the tool with a work-piece until a predetermined pres- 75

sure is experienced by said abutment means, and coupling mechanism including clutch means associated with one of the parts and adapted to grip the other part when said parts are moved 5 into juxtaposition so as to establish driving connection between them, said clutch mechanism being releasable to effect the separation of said driving means and cutting tool upon the completion of the cutting stroke of said tool whereby to prevent the tool from being drawn in a reverse direction through the work piece.

6. In material working apparatus, a rotary driving spindle, means for supporting said spindle, a rotary tool member adapted to be driven 15 by said spindle, a clutch mechanism positioned in substantial axial alinement with said spindle and said rotary member for automatically connecting said spindle and member for rotary driving purposes when said parts are relatively 20 moved into juxtaposition, said clutch mechanism including a sleeve driven by the spindle and locking means shiftable transversely within the sleeve for automatically and drivingly connecting it with said rotary member as said parts are 25 moved into association with each other, and means for effecting relative movement of said parts.

7. In material working apparatus, a rotary driving spindle, means for supporting said spindle, a rotary tool member adapted to be driven 30 by said spindle, a clutch mechanism positioned in substantial axial alinement with said spindle and said rotary member for automatically connecting said spindle and member for rotary driving 35 purposes when said parts are relatively moved into juxtaposition, said clutch mechanism including a sleeve and means shiftable radially within sleeve for automatically locking said sleeve for rotary driving purposes to one of said 40 rotary parts as said parts are moved into association with each other, and means for effecting relative movement of said parts.

8. In material working apparatus, a rotary driving spindle, means for supporting said spindle, a rotary tool member adapted to be driven 45 by said spindle, a clutch mechanism positioned in substantial axial alinement with said spindle and said rotary member for automatically and rotatively connecting said spindle and member 50 when said parts are relatively moved into juxtaposition, said clutch mechanism including a sleeve, locking means carried thereby for rotatively connecting said sleeve with said tool member, annular means surrounding said sleeve and 55 shiftable longitudinally thereof for automatically controlling said locking means as the spindle and rotary tool member move into association with each other, and means for effecting relative movement between said spindle and rotary tool 60 member.

9. In material working apparatus, a rotary driving spindle, means for supporting said spindle, a rotary tool member adapted to be driven 65 by said spindle, a clutch mechanism positioned in substantial axial alinement with said spindle and said rotary member for automatically and rotatively connecting said spindle and member when said parts are relatively moved into juxtaposition, said clutch mechanism including a 70 sleeve, locking means shiftable within said sleeve for establishing a driving coupling between the sleeve and tool member, a collar shiftable longitudinally of said sleeve for actuating said locking means, resilient means for shifting said collar in a given direction as the spindle and rotary

tool member reach a predetermined relative position, and means for effecting relative movement between said spindle and rotary tool member.

10. A boring machine including a support, a self-contained boring head reciprocably mounted upon said support, said boring head including a plurality of driving spindles and means for imparting rotation thereto, a shiftable table having a plurality of stations for positioning work pieces to be acted upon by cutting tools actuated by 10 said boring head and for receiving and discharging work pieces during the functioning of said boring head, boring tools supported by said table and adapted to be positioned in substantial alinement with companion spindles in said head, 15 means mounted on said table for supporting said boring tools independently of a supported work piece, clutch mechanisms for automatically coupling the spindles with said boring tools at a predetermined interval during the cycle of 20 reciprocation of said boring head, hydraulic mechanism for imparting rapid and slow movement to said head, means for preventing operative engagement of the tools with the workpiece until the clutch mechanism has operated 25 to complete the coupling of the spindles with the boring tools and means for automatically controlling the speed and direction of movement of said boring head, whereby the automatic coupling of the spindles with the boring tools 30 occurs during the rapid advancement of the head.

11. In a boring machine of the class described for simultaneously boring a plurality of spaced sections in a work piece, a bed, a head horizontally shiftable upon the bed, a rotary driving spindle mounted in said head, a shiftable table having a plurality of stations for receiving work to be acted upon, means at each station supported independently of the work and providing 35 spaced bearings for a boring bar having axially spaced cutting elements, a clutch mechanism on said spindle for effecting the automatic coupling of said spindle with a boring bar supported in said spaced bearings whereby to effect 40 the simultaneous boring of said spaced sections in the work piece, and means for controlling the automatic shifting of said spindle head, said table being shiftable upon the completion of the cutting stroke of the boring bar in a manner to 45 bring a previously positioned boring bar into proper alinement with the clutch mechanism on the spindle.

12. In a boring machine of the class described for simultaneously boring a plurality of spaced 55 sections in a work piece, a bed, a head horizontally shiftable upon the bed, a rotary driving spindle mounted in said head, a shiftable table having a plurality of stations for receiving work to be acted upon, means at each station supported 60 independently of the work and providing spaced bearings for a boring bar having a plurality of axially spaced cutting elements, a clutch mechanism on said spindle for effecting the automatic coupling of said spindle with a boring bar supported in said spaced bearings whereby to effect 65 the simultaneous boring of the spaced sections in said work piece, means for controlling the automatic shifting of said spindle head, said table being shiftable upon the completion of the cutting stroke of the boring bar in a manner to 70 bring a previously positioned boring bar into proper alinement with the clutch mechanism on the spindle, and a boring bar mounted in said spaced bearings, said bar having a plurality of 75

- axially spaced cutter elements extending radially thereof for cutting the surface of a work piece mounted on the table.
13. A boring machine of the class described including a bed, a horizontally reciprocable head on said bed, a rotary driving spindle in said head, a shiftable work supporting table, bearing means on said table for supporting a boring tool in position to be driven by said spindle, a clutch mechanism for automatically engaging a boring tool on the table, impositive means spaced from said clutch mechanism for engaging the extremity of the boring tool oppositely disposed from the clutch mechanism, whereby to enable the initial coupling of the spindle with the boring bar but automatically yieldable in response to continued advancement of the boring bar through the work piece, and means for controlling the movement of the spindle head.
14. A boring machine of the class described including a bed, a head horizontally reciprocable thereon, a driving spindle mounted within said head, a table for supporting a work piece, bearing means mounted directly on said table including spaced bearing members, a boring bar mounted in said bearing means having axially spaced cutting elements adapted to simultaneously cut a plurality of spaced cylindrical surfaces in a work piece disposed in axial alignment, at least one of said bearings being positioned intermediate said cutting elements, coupling means for automatically effecting the coupling of the driving spindle with the supported boring bar, and means for controlling the reciprocation of the spindle supporting head.
15. A boring machine of the class described including a bed, a head horizontally reciprocable upon said bed, a rotary driving spindle mounted in said head, means for automatically controlling the rate and direction of movement of said head, a manually manipulated rotary table operable independently of said head, said table having a plurality of stations whereby one station supports a work piece in position to be acted upon by a boring tool driven by said spindle and the other station is simultaneously positioned for convenient access by an operator to mount and dismount work pieces, and foot operated means including a cam having an axis extending transversely with respect to the axis of the table for elevating the table and means for simultaneously releasing the table to permit manual shifting thereof.
16. A boring machine of the class described including a bed, a head horizontally reciprocable upon said bed, a rotary driving spindle mounted in said head, means for automatically controlling the rate and direction of movement of said head, a manually manipulated rotary table operable independently of said head, said table having a plurality of stations whereby one station supports a work piece in position to be acted upon by a boring tool driven by said spindle and the other station is simultaneously positioned for convenient access by an operator to mount and dismount work pieces, a cam having an axis extending transversely with respect to the axis of the table for vertically shifting the table to render the same manually rotatable, a table locking mechanism, and foot control means for controlling the simultaneous functioning of said table shifting means and said table locking mechanism.
17. A boring machine of the class described including a bed, a head horizontally reciprocable upon said bed, a rotary driving spindle mounted in said head, means for automatically controlling the rate and direction of movement of said head, a manually manipulated rotary table operable independently of said head, said table having a plurality of stations whereby one station supports a work piece in position to be acted upon by a boring tool driven by said spindle and the other station is simultaneously positioned for convenient access by an operator to mount and dismount work pieces, a cam engaging the lower end of said support member for vertically shifting the table to render the same manually rotatable, latch means for securing the table in proper position, and foot control means including mechanism for contemporaneously governing the operation of the latch means and the cam for vertically shifting the table.
18. A boring machine including a bed, a spindle head horizontally reciprocable thereon, a driving spindle mounted within said head, a table for supporting a work-piece, spaced bearings carried directly by said table and adapted to support a boring bar, a boring bar mounted within said bearings equipped with axially spaced cutting elements adapted to contemporaneously cut a plurality of cylindrical surfaces disposed in axial spaced alignment within a work-piece carried by the table, at least one of said bearings being positioned intermediate the spaced cutting elements. coupling means for automatically effecting the coupling of the driving spindle with the supported boring bar, means for controlling the reciprocation of the spindle supporting head, and means for preventing contemporaneous operative engagement of the cutting elements with the cylindrical surfaces of a work-piece until the coupling of the spindle with the boring bar has been completed.
19. In material working apparatus of the class described, a support, a head horizontally reciprocable upon said support having a rotary driving spindle, means for moving said head at various speeds along said support including a hydraulic actuator and a variable displacement pump connected therewith, a rotary table including two work stations each station comprising substantially one half of the table space for retaining a work piece, a cutting tool adapted to be positioned in substantial alignment with the spindle of the head, one of said stations locating the work in position to be acted upon while the other station is positioned out of the path of movement of the tools to permit the reception and discharge of the work, means on said table for supporting said cutting tool independently of a supported work piece, clutch mechanism for automatically connecting the spindle with the rotary cutting tool at a predetermined interval of the cycle of reciprocation of said head, means for preventing operative engagement of the cutting tool with a supported work piece until the connection between the spindle and the tool has been completed, and control mechanism for governing the rate of displacement of said pump in accordance with the required rate of travel of said head.
20. In material working apparatus of the class described, a support, a driving spindle reciprocably mounted upon said support, means for shifting said spindle at a relatively rapid rate and for shifting said spindle at a slower rate for feeding purposes including a hydraulic actuator and a variable displacement pump connected therewith, a rotary cutting tool having a plurality of axially spaced cutting elements and adapted to be positioned in substantial alignment with said

5 spindle, a work-carrier, means mounted on said carrier including a plurality of axially spaced bearings for supporting said rotary cutting tool independently of a supported work piece, a shiftable support for said tool, control means for governing the rate of displacement of said pump and thereby causing the speed of travel of the spindle to be varied from the rapid to the slower rate at a predetermined interval, a clutch mechanism 10 operable contemporaneously with the functioning of said control means for governing the coupling of the spindle and tool, said coupling occurring during the rapid advancement of said spindle, and means for preventing operative engagement 15 of the tool with the work-piece until the coupling of the spindle and the tool has been completed.

20 21. A boring machine of the class described including a bed, a horizontally reciprocable head on said bed, a rotary driving spindle in said head, a 25 shiftable work supporting table, bearing means on said table for supporting a boring tool in position to be driven by said spindle, a clutch mechanism for automatically engaging a boring tool on the table, abutment means spaced from said clutch mechanism and adapted to be engaged by the extremity of the boring tool oppositely disposed from said clutch mechanism, said abut-

ment being yieldable to pressures in excess of the pressure required to effect the initial coupling of the spindle with the boring bar whereby to enable the automatic continued advancement of the boring bar through the work piece, and means for controlling the movement of the spindle head. 5

22. A boring machine of the class described including a bed, a horizontally reciprocable head on said bed, a rotary driving spindle in said head, a shiftable work supporting table, bearing means 10 on said table for supporting a boring tool in position to be driven by said spindle, a clutch mechanism for automatically engaging a boring tool on the table, abutment means including a horizontally disposed shiftable member spaced from 15 said clutch mechanism and adapted to be engaged by the extremity of the boring tool oppositely disposed from said clutch mechanism, said abutment being yieldable to pressures in excess of the pressure required to effect the initial coupling of the 20 spindle with the boring bar whereby to enable the automatic continued advancement of the boring bar through the work piece, and means for controlling the movement of the spindle head. 25
